ELECTROMAGNETIC REPRODUCTION OF SOUND AND OTHER WAVE MOTIONS

Frank M. Best, New York, N. Y., assignor to
Dorothy Sparrow Best

Application June 9, 1928, Serial No. 284,020

4 Claims. (Cl. 179—110)

My invention relates to a new and improved method for the electromagnetic reproduction of sound and other wave motions, and a new and improved mechanism therefor.

5 One of the objects of my invention is to provide a new and improved method whereby the audio currents produced by a radio receiving set, electric pick-up, or the like, can be caused to reproduce the original sound waves, with great 10 volume, and also with substantially uniform fidelity over a very wide range of tone.

Another object of my invention is to provide an improved driving unit for telephones, loud speakers or the like, which can deliver sound of 15 great volume and of correct tone.

Another object of my invention is to provide a driving unit in which sound waves, or other similar waves having frequencies above the audible range, shall be reproduced by means of waves 20 electromagnetically induced in a suitable armature, and with little or no bodily movement of the armature itself.

The present invention also contemplates an electromagnetic device for translating electrical 25 vibrations into mechanical vibrations wherein this translation is accomplished by vibratory movements within an armature supported in so rigid a manner as to be immovable. It has a stationary magnetizable field structure provided with 30 fixed field coils to receive the voice currents (or other currents of an inconstant nature), and an armature rigidly connected to a resonator such as a sounding board, and a rigid mounting for the armature.

35 For sound reproduction the preferably form of resonator is made of light wood such as spruce impregnated with rubber solution or natural latex, the rubber being in the unvulcanized state. These sounding boards may range in size from 40 20 x 30 in. to 20 x 32 ft. When so operated these sounding boards (made for example as shown in my application Serial No. 458,598, filed May 31, 1930, Methods of and apparatus for utilizing energy of a vibratory nature) are capable of re-

45 producing sounds throughout the entire audible range from 13 vibrations to 17,000 vibrations per second and indeed go far above the limits of audibility, for example to at least 40,000 vibrations per second. These sounding boards may be 50 from one-half to one-quarter of an inch thick and are secured to exceedingly rigid supports which in turn carry the field structure of the electromagnetic units so that there is no possibility of movement of the unit relative to the resonator. 55 One or more units may be employed and the

armature of each unit is rigidly connected to the sounding board. Each specific area of the resonator has a natural frequency and these natural frequencies extend throughout the range above given. When the coils of the units are 5 energized, the particular area of the sound board or resonator having the natural frequencies of the energizing current receives this vibratory energy and acts as a reflex driver to multiply the effect many times. The resonator is so rigid and 10 strong that the unit does not have the power that would be required for bending or deflecting it (as a beam) but yet it may be set into violent vibration by a very small input in the voice coils. With other forms of resonator or driver the armature 15 may be made to vibrate at frequencies in the order of several hundred thousand cycles per second.

The vibratory movement of the armature appears to be within the armature itself and not to be in the nature of a bodily movement of the 20 armature. It seems to be analogous to the vibration of the armature of an ordinary electric motor which has been overloaded until it stalls, whereupon it starts to vibrate. Very narrow clearances 25 may be employed between the armature and field structure without striking of the parts and careful tests negative the possibility of actual bodily movement of the armature.

Other objects of my invention will be set forth in the following description and drawing which 30 illustrates a preferred embodiment thereof, it being understood that the above general statement of the objects of my invention is intended merely to generally explain the same and not to limit it in any manner.

35 Fig. 1 is a top view illustrating one embodiment of my invention.

Fig. 2 is a sectional view on the line 2—2 of Fig. 1.

Fig. 3 is a sectional view on the line 3—3 of Fig. 1.

Fig. 4 is a perspective view of the armature employed.

Fig. 5 is a diagrammatic view of one of the circuits that may be employed.

In making driving units for loud speakers or the like, it has heretofore been customary to use an armature resiliently supported between the poles of a magnet, which was either a permanent magnet or else had field coils. The field of the 50 magnet was varied by means of current passing through a coil which was either wound upon the pole pieces of the magnet or else upon the armature itself. This current was for example, the audio current output of a radio receiving set so 55

that the armature was caused to vibrate in accordance with the audio current variations, to actuate a diaphragm which was either the diaphragm of a horn, or else vibrated in free air.

5 These resiliently supported armatures of the prior art had bodily movement as well as vibratory movement and, hence, the inertia of the armature always seriously affected the correctness of the reproduced sound and in addition such unit 10 could not take much power because if the armature vibrated too far it collided against the adjacent pole pieces due to the fact that a small air gap in the magnetic circuit was necessary for maximum efficiency.

15 According to my invention the armature is rigidly mounted so that if there is any movement thereof as a whole, it is imperceptible. The varying electromagnetic field produced by the audio current is utilized for producing vibratory 20 waves in the material of the armature itself unaccompanied by bodily movement. These waves may be compared with the waves in a sonorous body such as a bell, a length of railroad track, or the like, when tapped by a light blow. Such 25 a blow produces a large volume of sound without bodily movement. The waves produced in the armature are taken up by the rigid support and reflexed or reflected back and forth by it so as to build up the amplitude of the vibration without 30 bodily movement. These amplified waves are transmitted to the diaphragm or other mechanical element which produces sound waves.

As shown in Fig. 1, one of the embodiments 35 of my device comprises a magnet M which may either be a permanent magnet or may have a field coil. I have found that satisfactory results can be secured with a permanent magnet saturated so as to have a maximum pull. The magnet is provided with pole pieces 1 and 2, which 40 are provided with inwardly directed projections 3, 4, 5 and 6. Four audio or actuating coils C are wound upon the extensions 3, 4, 5 and 6, the 45 said coils being arranged in pairs, each pair being located upon a pair of adjacent pole piece extensions.

As shown in Fig. 4, the armature A has enlarged tapered ends and it is rigidly connected by a metal bar A' to a supporting block B. The 50 armature A may be made of soft iron, or any other permeable material having little or no residual magnetism.

A yoke Y has its ends connected to the pole pieces and to their extensions by means of bolts 55 1 and 8 and nuts 9 and 10. The pole pieces 1 and 2 are connected to the ends of the magnet M by means of screws 19 and 20. The block B is connected to yoke Y by screw 14. A terminal member 11 is clamped between nut 10 and an 60 upper nut 10'. The terminal member 11 is made of insulating material and two binding posts 12 having terminal lugs 16 are mounted thereon. The leads L for the coils C are connected to said binding posts. The coils C may be connected in 65 any suitable manner, to vary the impedance of the circuit as desired. In the embodiment shown, the four coils C are shown as connected in series-parallel, to provide a circuit of maximum impedance, but this is merely illustrative.

70 The armature A is connected by a rod 18 to a diaphragm D (diagrammatically illustrated) which may be a diaphragm or sounding board of any desired type. I prefer to use a flat sounding board made of a light wood, such as spruce, im- 75 pregnated with rubber solution, or natural latex,

the rubber being in the unvulcanized state. I also may use several units with a single sounding board capable of vibration over a wide range, each unit being intended to reproduce a given range of tones, as determined by the characteristics of the immediate neighborhood of the sounding board. The units for reproducing the higher tones are at or near the centre of the flat sounding board. The block B is rigidly connected by screw 14 to the middle of yoke Y.

5

10

The operation of the device is as follows:

Assuming that the pole-piece projections 3 and 5 are "North" and the pole-piece projections 4 and 6 are "South", the magnet flux passes along four air gaps, and across the ends of the armature A. These air gaps can be made very narrow, as narrow as 0.008 inch because the armature A has either no movement, or an imperceptible movement, due to the fact that it is connected by a strong, non-resilient metal bar (preferably 20 bell metal) to an immovable block B.

15

The pulsating current in each pair of coils C acts to reinforce or weaken the magnetic flux across the adjacent air gaps. I prefer to so wind the coils as to simultaneously and equally vary 25 the magnetic flux at each end of the armature A. However, it would not be departing from the invention if the flux was strengthened at one end of the armature A and was simultaneously weakened at the other end thereof.

30

Since a very strong magnetic field is produced by the magnet M, and the air gaps are very narrow, the varying magnetic field produces waves in the material of armature A. The nature of these waves is not definitely understood but from 35 certain experiments they seem to be of a rotary or oscillatory nature about the axis of the supporting bar somewhat analogous to the rotation of the vibratory waves in a bell when it is sounded. The waves produced in the armature 40 are transmitted into the rigid support which returns them toward the armature. This process is continued so that the magnitude of the waves is built up. Their magnitude is exceedingly small even though the sounding board to which 45 the armature is attached may have a ripple-like vibration of considerable magnitude and easily felt by the hand, without any deflection of the sounding board. These waves are transmitted along the metal rod 16 to the diaphragm, sounding board or the like. These vibrations are 50 reflexed in the material of the armature and the diaphragm and propagate sound of great penetration and volume and with remarkable fidelity.

50

Hence considerable power can be supplied to 55 the coils C without causing the armature A to click against the pole piece, and sufficient power should be supplied to produce waves in the material of the armature A.

It is clear that all the parts, save the magnet 60 M, form a connected unit, which can be readily attached to the ends of the magnet M. If desired, the pole pieces 1 and 2 could be located to abut the end faces of the magnet M, instead of abutting the lateral faces of the ends of the legs 65 of said magnet.

I prefer that the block B, and the armature supporting arm A' should not be integral with armature A, so that said arm A' can be made of metal having greater strength than soft iron. 70 The arm A' and block B could be made of brass, bell metal or other non-permeable material. Likewise, the yoke Y is made of non-permeable material.

Owing to the rigid mounting of the armature 75

and the absence of bodily movement, inertia effects are eliminated and wave motions far above the frequencies of sound are available. The magnetic structure above shown is useful in other fields than sound reproduction, such for example as so called high frequency generation, when several of these units are combined, some used as motors and others as generators, all directly connected.

10 I have shown a preferred embodiment of my invention, but it is clear that numerous changes and omissions could be made without departing from its spirit.

I claim:

15 1. A loud speaker unit having two pairs of pole members, an armature made of permeable material and located between the pole members, said armature having a rigid support so as to be bodily immovable, so that four air gaps of substantially constant width are formed in the magnetic circuit, and coil means associated with each pole member and adapted to vary the flux through said air gaps and set up vibration within the armature and its support without producing 20 bodily movement of either the armature or its support.

25 2. A loud speaker unit having two pairs of pole members, an armature made of permeable material and located between the pole members, said armature having a rigid support so as to be bodily immovable, so that four air gaps of substantially constant width are formed in the magnetic circuit, and coil means associated with each pole member and adapted to vary the flux

through said air gaps and set up vibration within the armature and its support without producing bodily movement of either the armature or its support, said coil means comprising four coils respectively located on said pole members.

3. A loud speaker driving unit comprising a magnet, and a sub-unit connected to the pole portions of said magnet, said sub-unit comprising a yoke, each end of said yoke having a pole-piece and two pole-piece projections connected thereto, each pole piece being intermediate two pole-piece projections, a supporting block connected to said yoke intermediate the ends thereof, said block having an armature rigidly connected thereto, said armature being located intermediate the adjacent ends of said pole-piece projections to form four air gaps in the magnetic circuit, coils respectively wound on said pole-piece projections, said sub-unit being directly connected to said end-portions of the magnet through 20 said pole-pieces.

4. A loud speaker operating unit, comprising a support, a stationary magnet carrying a plurality of pairs of rigid, immovable pole pieces, energizing coils wound about the pole pieces and arranged to produce opposite poles adjacent an armature, an armature having tips close to the pairs of pole pieces and mounted on the support, the support being substantially rigid when subjected to attractive forces within the power of 30 the magnet, and a connection from the armature for transmitting sound wave vibrations therein to a sonorous body.

FRANK M. BEST.
